(57) **CLAIM**

The ornamental design for a water pump pulley, as shown and described.

DESCRIPTION

FIG. 1 is a front isometric view of our new design for a water pump pulley;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is plan view thereof;

FIG. 8 is a bottom plan view thereof;

FIG. 9 is a cross sectional view taken along the line 9-9 of FIG. 3;

FIG. 10 is a front isometric view of only the claimed portion thereof;

FIG. 11 is a bottom isometric view of only the claimed portion thereof;

FIG. 12 is a front view of only the claimed portion thereof;

FIG. 13 is a rear view of only the claimed portion thereof;

FIG. 14 is a left side view of only the claimed portion thereof;

FIG. 15 is a right side view of only the claimed portion thereof;

FIG. 16 is a top plan view of only the claimed portion thereof;

FIG. 17 is a bottom plan view of only the claimed portion thereof;

FIG. 18 is a cross sectional view taken along the line 18-18 of FIG. 12;

FIG. 19 is a top view illustrating environmental structure surrounding the water pump pulley; and,

FIG. 20 is a cross sectional view taken along the line 20-20 of FIG. 19.

The broken lines depict an environment of use and form no part of the claim.

1 Claim, 16 Drawing Sheets
